MAX KIELSLING AND ADOLPH J. KRIEGER, OF WATERBURY, CONNECTICUT, ASSIGNEES
TO G. E. PRENTICE MANUFACTURING COMPANY, OF NEW BRITAIN, CONNECTICUT,
A CORPORATION OF CONNECTICUT

SLIDER FOR FASTENERS

Application filed December 17, 1929. Serial No. 414,668.

This invention pertains to fastening devices of the class commonly known as separable, interlocking, or hookless fasteners of which the patent to Judson, 557,207, dated 5 March 31, 1896 may be cited as an early instance. Such devices are commonly employed for closing gaps or openings in garments, for example, sweaters, coats, leggings, overshoes etc., as well as for closing bags, 10 packages, tent flaps, automobile curtains and many other articles.

Usually the complementary series of fastener elements at the opposite edges of the gap are brought into cooperating relationship 15 by means of a slider having suitable cam-like guides properly shaped for the purpose. However, it has been recognized since as early at least as the Judson patent above referred to, that if the cam elements of the 20 slider are of such slope as to ensure ease of operation, the slider may slip lengthwise of the closed fastener in response to stresses tending to open the gap, thus allowing the gap to open inadvertently, unless some means 25 be provided for positively holding the slider at the limit of its travel with the gap closed. In the Judson patent referred to, a crude form of retaining means comprising loops adapted to engage appropriate pins was pro- 30 vided for the purpose, and since the Judson patent, many other retaining devices have been proposed.

Since rapidity of actuation is one of the 35 important advantages claimed for fasteners of this type, it is obvious that any retaining means requiring careful manipulation by the operator detracts from the value of the device, and for this reason, attempts have 40 been made to embody the retaining means in the actuating pull or tab in such a way that when the pull or tab is released after actuation of the slider and allowed to hang vertically down, the slider is automatically retained in position. However, in most prior 45 devices of the kind known to us, the retaining means involves the use of a member or members adapted to enter between adjacent fastener elements of the series, and when 50 thus designed, such retaining devices tend

to displace or distort the fastener elements so that they will not operate smoothly.

In accordance with the present invention, we provide a slider having a very simple, inexpensive and reliable form of pull controlled 55 retaining means which does not distort or displace the opposed fastener elements; which is durable and not liable to injury from contact with external objects; which does not add to the bulk or necessitate a 60 change in the shape or general appearance of the sliders; and which will dependably retain the slider in adjusted position with the pull in depending position.

In the accompanying drawing we have il- 65 lustrated a preferred embodiment of our invention wherein the slider is adapted for use in closing the gap by movement upwardly, and a modification thereof showing the invention applied to a slider which is moved 70 downwardly for closing the gap.

In the drawing: Fig. 1 is a fragmentary front elevation, to large scale, illustrating a fastener of the type referred to, provided with a slider embody- 75 ing the present invention, and wherein the slider is moved upwardly for closing the gap;

Fig. 2 is a vertical section, substantially on the line 2—2 of Fig. 1, showing the parts po- 80 sitioned to retain the slider in adjusted position, certain of the fastener elements being shown in section, but omitting the stringers;

Fig. 3 is a side elevation of another embodiment of the invention, indicating the changes 85 necessary to permit use of the slider for closing a gap by downward movement;

Fig. 4 is a plan view to large scale of a blank suitable for use in forming the slider body herein illustrated;

Fig. 5 is a top edge view of a novel pull de- 90 vice forming a part of the improved slider;

Fig. 6 is a plan view to large scale of a blank useful in the preparation of the friction retaining device forming a part of the inven- 95 tion; and

Fig. 7 is an edge elevation of the friction device completed.

Referring to the drawing and particularly to Figs. 1 to 3, the numerals 1 and 2 designate 100

tapes or stringers to which the opposed series of fastener elements 3 are respectively connected. While it is usual to furnish fasteners of this kind to the trade in the form of a complete structure comprising the tapes or stringers upon which the series of fastener elements are mounted, it is to be understood that so far as its broader aspects are concerned the present invention is not necessarily limited to the 10 inclusion of these tape members, since it is conceivable that the fastener elements might be applied directly to the edges of the material in which the gap occurs and when in the appended claims the term "stringer" is employed, it is to be understood as broadly comprehending any flexible element forming in effect one edge of the gap to be closed. For convenience in illustration we have shown the fastener elements 3 as of the type more 20 fully described and claimed in the patent to Prentice and Legat No. 1,658,392, dated February 7, 1928, but it is to be understood that the present invention is not to be limited to such specific use but is applicable to fasteners of other types falling within the general class.

For use in moving the fastener elements of the opposed series into operative relationship, we employ a slider S which in general may be 30 of a type well known in the art as, for example, that shown in the patent to Prentice No. 1,677,408, July 17, 1928, although we have here illustrated the slider as of specifically novel form and construction. Thus, our improved slider comprises the front wing 4 (Fig. 2) and the rear wing 5 united by the neck 6, and this slider body may be formed conveniently from a unitary piece of sheet metal shaped to provide the blank shown in 40 Fig. 5. This blank comprises the wing portions 4^a and 5^a integrally united by the neck 6 and having the elongate guide tongue 7 projecting integrally from the outer end of the wing portion 4^a. This elongate guide tongue 45 7 is provided near its free end with a portion 8 of reduced width, beyond which the extremity 9 of the tongue again increases in width. The neck 6 is provided at its opposite edges with integral tabs 10 and 11 and it is to 50 be understood that, as usual, in the manufacture of sheet metal sliders, the lateral edges of the wing portions 4^a and 5^a are bent inwardly to form suitable guide flanges. The blank, as shown in Fig. 5, is bent at the junctions of the wing members with the neck so as to bring the wing portions into substantially parallel relation, and the guide tongue 7 is then bent to provide the lower substantially horizontal portion 12 (Fig. 2), the substantially vertical guide portion 13 which is parallel to and spaced from the front surface of the wing 4, and the top member 14 which extends rearwardly across the top of the slider. The reduced portion 8 of the tongue 55 is disposed between the tabs 10 and 11 which

are turned upwardly and then inwardly as indicated in Fig. 1 so as to clamp the end portion of the tongue between them.

The front wing 4 is provided with an opening 15 for the passage of the friction shoe 16. 70 This friction shoe is conveniently formed as an integral U-shaped bend in a sheet metal rocker member comprising the divergent stiffly resilient arms 17 and 18. This rocker may be made from a piece of sheet material of the 75 general shape indicated in Fig. 6 having the central neck portion 16^a of such width that when bent to the shape shown in Fig. 7 it may pass freely and without binding through the opening 15. This blank also comprises the end portions 17^a and 18^a of greater width than the neck and adapted to form the arms 17 and 18. Preferably the outer ends of these arms are recessed or forked to provide the retaining fingers 19 which engage the opposite 80 edges of the guide member 13 in order to hold the rocker in properly assembled relation to the slider body. With this simple arrangement it is not necessary to employ rivets or other fasteners for holding the retaining 90 means in assembled relation to the other parts, and the improved structure is but slightly more expensive to make than usual constructions.

The pull or tab 20 is here shown as of a 95 general shape commonly employed in sliders of this type and is preferably made from sheet material of suitable character. In accordance with the preferred form of the invention this tab or pull is provided with an opening 21 through which the guide member 13 passes, the guide and opening supporting the pull pivotally and permitting the pull to be moved from one end to the other of the slider. As most clearly illustrated in 100 Figs. 2, 3 and 5, the pull 20 is provided at its upper end with a transversely extending offset 22 at its inner side, said offset having a recess in its edge forming the spaced fingers 23. As indicated in Figs. 2 and 3, the offset 105 22 of the pull is disposed between the front face of the rocker and the rear face of guide 13. When the pull is swung outwardly at a substantial angle to the direction of movement of the slider in order to facilitate actuation of the latter, the offset is thereby disposed more nearly parallel to the guide 13 and moves freely in the space between the guide 13 and the rocker, so that the position 110 of the rocker is not affected substantially by the pull, thus permitting the shoe 16, which fits loosely in the opening 15, to retreat therefrom, and preventing any substantial pressure of the shoe against the fastener elements 115 so that the slider can be moved freely in either direction. Assuming that the slider is moved upwardly to close the fastener, as in the arrangement of Figs. 1 and 2, the pull 20, when released by the operator, will hang 120 downwardly from the lower end of the guide 125 130

- 13, the weight of the pull tending to swing it to a substantially vertical position. Since the offset 22 is of substantial width, the vertically depending pull causes the front and rear parts of the offset 22 to contact respectively with the guide 13 and with the lower arm 17 of the rocker, and the offset thus acts as a cam for forcing the arm 17 against the wing 4. By reason of the divergent arrangement of the arms 17 and 18, the end of the arm 18 now bears resiliently against the inner surface of the guide 13 which forms a slightly resilient abutment, and the pressure of the offset against the lower arm 17 causes the shoe 16 to project through the opening 15 and press forcibly against the fastener elements, pushing them against the rear wall 5 of the slider and exerting a frictional drag which effectively prevents accidental movement of the slider. To assure the maintenance of this locking or holding action, the pull 20 may be swung rearwardly by pressure of the fingers toward the plane of the wing 4 (with reference to the pivotal support of the pull upon the guide 13) so that the offset will assume an inclined position (Fig. 2). In thus pressing the pull rearwardly, the rocker arms 17 and 18 as well as the guide 13 may spring slightly, being formed of resilient material, and thus when the pull is disposed in its rearward position, as described, the pressure of the parts will so retain it until it is positively swung forwardly beyond the vertical plane.
- 35 While this improved slider is very useful for closing the gap by upward pull, it may be noted that if inverted, as for closing a gap by downward pull, the pull 20 when released would hang down in such position that the gap between the parts 23 of the offset would receive the guide 13 and no locking pressure would be exerted on the arm 17. Thus, if it be desired to provide a slider useful in closing a gap by downward movement, it is necessary, as indicated in Fig. 3, to reverse the arrangement of the pull as respects the arms of the rocker, so that when the pull is in depending position the offset will engage the arm 18 instead of the arm 17. By providing sliders of the two types illustrated in Figs. 2 and 3 respectively, the user may select that best suited to his requirements, that is to say, that slider which is adapted to close the gap by upward or downward movement as the particular purpose may demand.
- While we have illustrated certain desirable embodiments of the invention by way of example, we wish it to be understood that the invention is not to be limited by the arrangement specifically shown and described but is broadly inclusive of such modified constructions as fall within the range of equivalency of the appended claims.
- We claim:
- 65 1. A slider for fasteners of the kind having stringers carrying series of interengaging fastener elements, said slider comprising front and rear wings, one of said wings having an opening therein, and an elongate guide loop extending longitudinally of that wing which has the opening, an actuating pull having an aperture for the reception of the guide loop and movable along the latter substantially from one end to the other of the slider, said pull having an offset cam portion adjacent to its aperture, and slider retaining means comprising a friction shoe provided with divergent arms, one of said arms engaging the guide loop and the other being engaged by the offset cam portion of the pull while the slider is retained in adjusted position, said friction shoe being disposed in the opening in the wing and being operative to exert frictional pressure against the front faces of the fastener elements when the pull occupies a predetermined position thereby to hold the slider against accidental movement longitudinally of the series of fastener elements. 70
- 75 2. A slider for fasteners of the kind having stringers carrying series of interengaging fastener elements, said slider having front and rear wings, one of said wings having an opening therethrough and an elongate guide loop extending longitudinally of the wing which has the opening therein, a pull having an aperture for the reception of the guide loop and movable along the latter substantially from one end to the other of the slider, said pull having a cam portion adjacent to its aperture, and slider retaining means comprising a rocker having a centrally disposed friction shoe and divergent stiffly resilient arms, each arm having retaining fingers at its free end operative to engage the lateral edges of the guide loop whereby to position the rocker, said friction shoe passing freely through the opening in the wing and being engageable with the front faces of the fastener elements for frictionally retaining the slider in adjusted position when the pull occupies a predetermined position. 80
- 85 3. A slider for fasteners of the kind having stringers carrying series of interengaging fastener elements, said slider having front and rear wings, the front wing having an opening therethrough and an elongate guide loop extending longitudinally of the front wing, a pull having an aperture for the reception of the guide loop, the pull being movable along the guide loop substantially from one end to the other of the slider, said pull having an offset cam portion, and retaining means comprising a rocker consisting of a unitary piece of sheet material having a central U-shaped bend constituting a friction shoe and having divergent stiffly resilient arms provided with loop engaging elements at their free extremities, said friction shoe projecting freely through the opening in the front wing for 90
- 95 100 105 110 115 120 125 130

- engagement with the front faces of the fastener elements and being operative to retain the slider in adjusted position when the pull is so disposed that its offset cam portion 5 presses one of the arms of the rocker substantially into contact with the outer surface of the front wing.
4. A slider for fasteners of the kind having stringers carrying series of interengaging 10 fastener elements, said slider comprising front and rear wings, one wing having an opening therethrough, a longitudinally extending guide on said front wing and bridging the opening, a pull movable along said 15 guide substantially from one end to the other of the slider, and a retaining member projecting through the opening in the front wing for engagement with the fastener elements of the series, said pull having a part operative, 20 by engagement with the retaining member when the pull is in depending position, positively to press the retaining member into operative relation with the fastener elements.
5. A slider for fasteners of the kind having 25 stringers carrying series of interengaging fastener elements, said slider comprising front and rear wings, the front wing having an opening therethrough and an elongate guide loop extending longitudinally of the slider 30 and spaced from the front wing, a friction member having a shoe portion extending through the opening in the wing for engagement with the fastener elements, and a pull movable along said guide loop, said pull having 35 an offset part provided with spaced cam fingers engageable with the friction member for pressing the shoe portion of the latter against the fastener elements when the pull is in depending position, said cam fingers 40 straddling the guide loop when the pull is positioned for use in moving the slider for closing the fastener whereby to avoid the application of locking pressure during such movement of the slider.
6. A slider for fasteners of the kind having 45 stringers carrying series of interengaging fastener elements, said slider having front and rear wings, the front wing having an opening therethrough and an elongate 50 guide, spaced from the front wing, retaining means disposed between the guide and the front wing and retained in position by engagement with said guide and front wing, said retaining means having a shoe projecting 55 loosely through the opening in the wing, and a pull movable longitudinally of the guide, the pull having parts engageable with the guide and with the retaining means respectively, for pressing and clamping the shoe 60 against the fastener elements when the pull occupies a predetermined position with reference to the guide.
7. A slider for fasteners of the kind having 65 stringers carrying series of interengaging fastener elements, said slider having

front and rear wings, the front wings having an opening therein and an elongate guide spaced from the front wing, a rocker comprising divergent arms disposed between the guide and front wing and adapted for alternative engagement with the guide, said rocker having a central portion projecting through the opening in the wing and constituting a friction shoe, and a pull device suspended from the guide, said pull device being engageable with that end of the rocker which at the time does not engage the guide whereby to force the friction shoe against the fastener elements.

8. A slider for fasteners of the kind having stringers carrying series of interengaging fastener elements, said slider having front and rear wings, the front wing having an opening therein, an elongate guide spaced from the front wing, a rocker disposed between the guide and front wing, said rocker having end portions alternatively engageable with the inner surface of the guide, and a central portion projecting through an opening in the wing and constituting a friction shoe for engagement with the fastener elements, and a pull device suspended from the guide and having an element engageable with one arm, at least, of the rocker for forcing the friction shoe against the fastener elements.

9. A slider for fasteners of the kind having stringers carrying series of interengaging fastener elements, said slider having front and rear wings, the front wing having an opening therein, an elongate guide spaced from the front wing, a rocker having a central part constituting a friction shoe disposed in the opening in the front wing and also comprising divergent arms adapted to engage the inner surface of said guide, and a pull suspended from the guide, said pull having a cam portion adapted simultaneously to react against the inner surface of the guide and one arm of the rocker respectively for forcing the pressure shoe against the fastener elements.

Signed by us at Berlin, Conn., this 14th day of December, 1929.
